UNITED STATES PATENT OFFICE.

COLUMBUS K. LASSITER, OF RICHMOND, VIRGINIA.

MANUFACTURE OF SUPERHEATER UNITS.

1,083,688.

Specification of Letters Patent.

Patented Jan. 6, 1914.

Application filed June 5, 1913. Serial No. 771,852.

To all whom it may concern:

Be it known that I, COLUMBUS K. LAS-
SITER, of Richmond, in the county of Henrico
and State of Virginia, have invented a cer-
tain new and useful Improvement in the
Manufacture of Superheater Units, of which
improvement the following is a specification.

My invention relates to superheater units
of the form ordinarily applied in locomotive
boiler superheaters of the fire tube type, and
its object is to provide a method of construc-
tion whereby superheater units of such char-
acter may be readily and inexpensively
manufactured, and which will render avail-
able, as constituents thereof, drop forged or
hydraulic pressed return bends, and to pro-
duce a superheater unit, as an article of
manufacture, which shall be of greater
strength, durability, and effectiveness in
service, than those of the ordinary construc-
tion, by reason of having its parts solidly
and securely connected together, and fully
exempt from liability to leakage at their
junctions.

25 The improvement claimed is hereinafter
fully set forth.

In the accompanying drawings: Figure 1
is a view in elevation, of a superheater unit
manufactured under my invention; Fig. 2, a
30 longitudinal section, on an enlarged scale,
through an end portion thereof; Fig. 3, a
view, in perspective, of a return bend body;
Fig. 4, a similar view of a return bend cap;
Fig. 5, a view similar to Fig. 2, showing a
35 modified form of return bend; Fig. 6, a lon-
gitudinal section through the same, on the
line *a a* of Fig. 5; and, Fig. 7, a transverse
section, on the line *b b* of Fig. 5.

As ordinarily constructed, superheater
40 units of the class to which my invention re-
lates are composed of parallel lines of seam-
less steel pipes and cast steel return bends,
the ends of the lines of pipe being connected
by tapping or threading them into the re-
turn bends. When so connected, leaks are
45 frequently developed at the joints, after the
units have been put in service, these being
due to imperfectly made or deteriorated
joints, or to strains exerted on the units in
removing them from the boiler tubes. The
50 cast steel return bends are also often found
to be defective by reason of the presence of
sand holes or other imperfections, necessi-
tating their rejection and loss. These objec-
55 tions, which are familiar to builders and op-

erators of locomotives fitted with super-
heaters, are, under my invention, effectively
eliminated.

Referring first to Figs. 1 to 4 inclusive of
the drawings, for the practice of my inven-
tion, I provide a plurality of pipes, 1, of
proper length and diameter, and return
bends for the connection of the ends of two
parallel lines of said pipes. The return
bends, which are formed either by drop forg-
ing or by hydraulic pressure, are, as shown,
of sectional construction, each return bend
comprising a hollow body section, 2, which
is continuously open at one end, in the form
of a flattened ellipse, and is turned, at its
opposite end, into two cylindrical open
ended projections, disposed side by side, and
matching with, that is to say, substantially
corresponding in diameter, and in thickness
of metal, with the ends of the pipes to be
connected, and a dished cap or cover section,
3, the form of which, at its open end is a
flattened ellipse, which corresponds with
that surrounding the open end of the body
section, as indicated in Figs. 3 and 4. The
connection of the two lines of pipe is ef-
fected by electrically welding the ends of the
cylindrical projections of a body section, 2,
of a return bend, to the corresponding ends
of the two lines of pipe, and similarly weld-
ing a cap section, 3, to the opposite end of
the body section. By reason of the corre-
spondence, in transverse section, and con-
sequent "matching", of the ends of the
pipes, body section, and cap, as above de-
scribed, which is a novel and characteristic
feature of my invention, there is no projec-
tion of metal beyond the abutting surfaces
to be welded, at any of the several welds, and
therefore the welding operation may be
quickly and economically effected by the ap-
plication of an alternating electric current
and end pressure. This would not be prac-
ticable if metal projected beyond the sur-
faces to be welded. The two lines of pipe
and the return bend are united by the above
operation so as to form a solid, and, for
practical purposes, an integral structure,
which presents no joints and is thereby ex-
empt from liability to leakage, and is not
subject to the loosening strains by which the
ordinary threaded connections are deterio-
rated and rendered unfit for efficient service.

Figs. 5 to 7 inclusive illustrate a struc-
tural modification of the return bend, which,

in this case, is provided with removable plugs for affording access, if desired, to the interior of the pipe lines. The body section, 2, is of similar form to that before described, 5 and a cap section, 3^a, is provided, which, instead of being cupped or dished, corresponds in transverse section throughout its length, to the open end portion of the body section, and its outer end, which is plane, is provided 10 with two openings, which are threaded, in line axially with the openings of the body section, to receive removable plugs, 5, which are cupped or hollowed interiorly, as shown, to prevent them from being burned out by 15 the action of the high heat to which they are subjected. Squared projections, 5^a, are formed on the plugs, for the application of a wrench in screwing them into and out of position. The pipe lines, 1, body section, 2, 20 and cap section, 3^a, are electrically welded together, as in the instance first described. By removing the plugs, a reamer may be inserted, for the purpose of truing out the end portions of the pipes.

25. My invention is, so far as my knowledge and information extend, differentiated from all constructions proposed in the prior art, by the provision, as described and shown, of an independent cap section, which is 30 welded to the open ended body section of the return bend after the cylindrical projections of the body section have been welded to the two pipe lines. In the latter welding operation, when performed by the resistance electric welding process, a "flash" or 35 inwardly projecting ring of metal is formed at the joints of the body section and pipe lines, the presence of which would so materially obstruct the bores of the pipes as to 40 render them unfit for service in a superheater unit. The opposite end of the body section being, as shown, either entirely open or closed by removable plugs, the flash can 45 be readily and quickly removed by the insertion and rotation of a reamer; before the cap is welded to the body section, and inasmuch as the inside transverse sectional area of the completed return bend is materially greater than that of the pipe lines, the reduction 50 thereof by the flash formed at the

joint of the body section and cap is inappreciable.

I claim as my invention and desire to secure by Letters Patent:

1. As a new article of manufacture, a 55 superheater unit comprising a return bend body having two cylindrical open ended projections disposed side by side at one of its ends, each matching the end of a line of superheater pipe and open at its opposite 60 end, two lines of superheater pipe, each electrically welded to the end of one of said projections, and a closure member electrically welded to the opposite end of the return bend body. 65

2. As a new article of manufacture, a superheater unit comprising a return bend body having two cylindrical open ended projections disposed side by side at one of its ends, each matching the end of a line of 70 superheater pipe, and being entirely open at its opposite end; a return bend cap matching the opposite end of the body; and two lines of superheater pipe, the return bend body and cap being electrically welded 75 one to the other on their matching surfaces and each of the lines of pipe being electrically welded to the matching end of one of the projections of the return bend body.

3. As a new article of manufacture, a 80 superheater unit comprising a return bend body having two cylindrical open ended projections disposed side by side at one of its ends, each matching the end of a line of superheater pipe, and being entirely open 85 at its opposite end; a return bend cap matching the opposite end of the body; two lines of superheater pipe, the return bend body and cap being electrically welded one to the other on their matching surfaces and 90 each of the lines of pipe being electrically welded to the matching end of one of the projections of the return bend body, and removable plugs threaded into the outer end of the return bend cap. 95

COLUMBUS K. LASSITER.
